UNITED STATES PATENT OFFICE.

EDWIN B. ADAMS, OF MARION, INDIANA.

DESIGN FOR A MEDICINE-TRAY.

53,651.

Specification for Design.

Patented July 29, 1919.

Application filed March 5, 1919. Serial No. 280,869. Term of patent 7 years.

To all whom it may concern:

Be it known that I, EDWIN B. ADAMS, a citizen of the United States, residing at Marion, in the county of Grant and State of Indiana, have invented a new, original, and ornamental Design for a Medicine-Tray, of which the following is a specification, reference being had to the accompanying drawing, forming part thereof.

Fig. 2 is a side elevation thereof.

I claim:

The ornamental design for a medicine tray, as shown in the accompanying drawing.

EDWIN B. ADAMS.
